MEANS FOR CONDENSING FLUIDS

Eno F. Renken, Dallas, Tex.

Application May 23, 1936, Serial No. 81,363

8 Claims.

(Cl. 261—91)

This invention relates to new and useful improvements in condensing apparatus.

One object of the invention is to provide an improved condensing apparatus wherein the comparatively cool condensed liquid is forced into intimate contact with the fluid to be condensed, whereby the temperature of the condensed liquid is utilized to aid in condensing said fluid.

Another object of the invention is to provide an improved condenser which is particularly adapted for use with refrigerating systems employing a volatile fluid, such as ammonia, as a refrigerating medium.

An important object of the invention is to provide the combination with a mechanical refrigerator of a self-contained condenser unit wherein the comparatively cool liquid condensate is utilized to condense the incoming hot gas, thereby eliminating the provision of an auxiliary cooling medium or unit.

A further object of the invention is to provide a condenser for a refrigerating system which system employs a compressor for circulating the refrigerating medium, the condenser including a sealed condensing chamber wherein the condensed liquid is maintained at a level; the compressor being located within the chamber whereby the hot gas is released into said chamber, and means for agitating or spreading the condensed liquid within the chamber, whereby the comparatively cool liquid condenses the gas and also cools the compressor by dissipating the heat incidental to its operation.

A particular object of the invention is to utilize the power of the compressor motor for agitating or spreading the condensed liquid within the condensing chamber, whereby said liquid is forced into intimate contact with the gas to be condensed.

A still further object of the invention is to provide an improved condenser which is constructed of a minimum number of parts and which is provided with cooling means, whereby it operates under lower temperatures, at all times, which greatly increases the efficiency thereof.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a transverse, vertical, sectional view

of a condensing unit, constructed in accordance with the invention.

Figure 2 is a horizontal, cross-sectional view taken on the line 2—2 of Figure 1.

Figure 3 is a view, similar to Figure 1, showing a water jacket surrounding the condenser, and

Figure 4 is a detail view of one form of agitator.

In the drawing, the numeral 10 designates a casing or housing which is preferably constructed of metal, or other suitable material. The casing 10 is provided with a bottom 10' and the upper end of the casing is flanged, whereby a top 11 may be bolted or otherwise secured thereto. The interior of the casing forms a condensing chamber 12. The casing is preferably cylindrical in shape 15 and has a plurality of radially extending fins 13 formed on its exterior surface and these fins serve to air cool the chamber 12.

The usual compressor and motor unit 14 of the refrigerating unit of an ordinary mechanical refrigerator (not shown) is bolted or otherwise removably fastened to the underside of the top 11, whereby when said top is mounted on the casing the compressor and motor depend into the condensing chamber 12 formed within the 25 casing 10. The compressor includes the usual cylinder 15 having the piston 16 operating therein. A gas inlet pipe 17 extends through the top 11 of the casing and is connected with the cylinder 15, whereby the hot gases are conducted to said 30 cylinder. A gas outlet pipe 18 leads from the piston and this pipe releases the gas into the interior of the condenser chamber 12. The piston 16 of the cylinder is reciprocated by a crank 19 which is formed on the shaft 20 of the motor. 35

The gas or vapor which is condensed within the chamber 12 will, of course, fall to the bottom or lower end of the chamber and will be condensed into a liquid form. The condensed liquid is conducted from the chamber 12 through an outlet 40 pipe 21 which extends radially through the wall of the casing 10. The pipe 21 is located at some distance from the bottom 10' of the casing and it is obvious that the location of said pipe will maintain a predetermined level of the condensed 45 liquid within the chamber 12.

For spraying the condensed liquid upwardly into the chamber 12 and into intimate contact with the incoming hot gases, the motor shaft 20 is extended downwardly from the crank 19 and 50 has its extreme lower end depending below the standing liquid level within the chamber. An agitator or spreader 22 is fastened on the lower end of the shaft 20 and is provided with a plurality of upwardly curved, radially extending 55

blades 23. Manifestly, when the motor and compressor are operating, the agitator 22 is rotated and serves to spray the condensed liquid standing within the casing upwardly into the chamber 12 and into intimate contact with the hot gas or vapor which is released into this chamber from the outlet pipe 18. The liquid which is sprayed upwardly is relatively cool and also contacts the motor and the compressor to aid in cooling these 10 parts.

The operation of the device is obvious. The hot gas will enter the compressor through the inlet pipe 17 and will be released into the condensing chamber 12 through the outlet pipe 18. At the same time, the agitator 22 will be rotated whereby the liquid condensate is sprayed upwardly within the chamber 12 into contact with this hot gas or vapor. The condensed liquid is comparatively cool and will materially aid to 20 effect a condensation of the gas or vapor within the chamber. It is a well known fact that a fine spray will more efficiently condense a gas or vapor and, therefore, the agitator is utilized to produce such a spray. The cooling fins 13 on the outer 25 surface of the casing 10 provide an increased surface for conducting away the heat within the chamber 12 to the outside air. These fins also aid in dissipating the heat of the standing condensed liquid in the bottom of the casing, whereby cooling 30 of said liquid will be increased.

It is pointed out that the unit is self-contained and may be readily employed with the usual mechanical refrigerator. By providing the removable top 11 and fastening the motor and compressor unit thereto, it is possible to remove said compressor and motor by merely removing said top. The liquid, which is sprayed upwardly, not only is utilized to condense the hot gases and vapors, but is also utilized to cool the motor and compressor, whereby these parts operate under a minimum temperature at all times, which greatly increases their efficiency.

The invention is not to be limited to the provision of the cooling fins 13 on the outer surface 45 of the casing 10, as various other means of cooling the chamber and dissipating the heat therein may be employed. In Figure 3, the casing is shown as surrounded by a suitable water jacket 24. This jacket is made in the form of a cylindrical housing having a closed bottom and being of a size considerably larger than the casing 10, whereby said casing may be housed therein. The walls of the casing 10 are spaced from the inner walls of the jacket 24 by suitable ribs 25. The 50 upper end of the jacket 24 is formed with an annular flange 26, whereby a suitable closure or cover 27 may be bolted or otherwise secured thereto. The inlet pipe 17 extends through an opening 28 in the top 27 and a suitable packing gland 29 may surround this pipe. The outlet pipe 21 which conducts the liquid condensate from the interior of the chamber 12 extends outwardly through an opening 30 formed in the wall of the jacket 24. Cold water, or some other cooling 55 medium, is introduced into the jacket to fill the space between said jacket and the casing 10, through an inlet pipe 31 which is located at the upper end of the jacket in the wall thereof. Manifestly, the water jacket acts as a cooling 60 medium to cool the chamber 12 and quickly dissipate the heat therein. The operation of this form is exactly the same as that shown in Figure 1.

It is pointed out that a particular type of agitator has been disclosed, but the invention is not

to be limited to an agitator of this construction. It is manifest that various types of agitators or spreaders may be employed and, so long as the power of the compressor motor is utilized to perform the spraying of the liquid, the purposes of 5 the invention are accomplished.

What I claim and desire to secure by Letters Patent, is:

1. A condenser for the refrigerating medium of a refrigerating system including, a casing having the motor and compressor of said system located therein, means for maintaining a level of the liquid condensate within the container, and means for releasing the fluid to be condensed from the compressor into the container above the liquid level, and means operated by the motor for spreading the liquid upwardly within the container into contact with the fluid to effect condensation thereof. 15

2. A condenser for the refrigerating medium of a refrigerating system including, a casing having the motor and compressor of said system located therein, means for maintaining a level of the liquid condensate within the container, means for releasing the fluid to be condensed from the compressor into the container above the liquid level, means operated by the motor for spreading the liquid upwardly within the container into contact with the fluid to effect condensation thereof, and a water jacket surrounding the container for cooling the same to enhance condensation of the fluid therein. 20

3. A condenser for the refrigerating medium of a refrigerating system including, a casing having the motor and compressor of said system located therein, means for maintaining a level of the liquid condensate within the container, means for releasing the fluid to be condensed from the compressor into the container above the liquid level, and an agitator secured to the motor shaft and 35 rotatable within the liquid level for spreading the liquid upwardly within the container into contact with the fluid to condense the same. 40

4. A condenser for the refrigerating medium of a refrigerating system including, a casing having the motor and compressor of said system located therein, means for maintaining a level of the liquid condensate within the container, means actuated by the rotation of the motor shaft for forcing the fluid to be condensed into the container above the liquid level, and an agitator secured to the motor shaft and rotatable within the liquid level for spreading the liquid upwardly within the container into contact with the fluid to condense the same. 45

5. A condenser for the refrigerating medium of a refrigerating system including, a casing having the motor and compressor of said system located therein, means for maintaining a level of the liquid condensate within the container, means for releasing the fluid to be condensed from the compressor into the container above the liquid level, an agitator secured to the motor shaft and rotatable within the liquid level for spreading the liquid upwardly within the container into contact with the fluid to condense the same, and a water jacket surrounding the container for cooling the same to enhance condensation of the fluid therein. 60

6. A condenser for the refrigerating medium of a refrigerating system including, a casing having the motor and compressor of said system located therein, means for maintaining a level of the liquid condensate within the container, means actuated by the rotation of the motor shaft for 65

forcing the fluid to be condensed into the container above the liquid level, an agitator secured to the motor shaft and rotatable within the liquid level for spreading the liquid upwardly within the 5 container into contact with the fluid to condense the same, and a water jacket surrounding the container for cooling the same to enhance condensation of the fluid therein.

7. The combination with a mechanical refrigerator of a self-contained condenser unit including, a closed casing forming a condensing chamber which has the motor and compressor of said refrigerator mounted in its upper end, whereby the motor shaft extends downwardly within the 15 chamber, means for maintaining a sufficient level of liquid condensate within the container to submerge the lower end of the motor shaft, means for releasing the fluid to be condensed into the container above said liquid level, and means 20 mounted on the lower end of the motor shaft for

spreading the liquid upwardly into contact with said fluid to effect condensation thereof.

8. The combination with a mechanical refrigerator of a self-contained condenser unit including, a closed casing forming a condensing chamber which has the motor and compressor of said refrigerator mounted in its upper end, whereby the motor shaft extends downwardly within the chamber, means for maintaining a sufficient level of liquid condensate within the 10 container to submerge the lower end of the motor shaft, means for releasing the fluid to be condensed into the container above said liquid level, and an agitator on the lower end of the motor shaft and contacting the liquid, whereby when 15 the motor is operated, the agitator is rotated to spread the liquid upwardly into contact with the fluid to effect condensation thereof.
